US00D363240S

United States Patent [19]**Hirakawa et al.**[11] **Patent Number:** **Des. 363,240**[45] **Date of Patent:** ****Oct. 17, 1995**[54] **SURVEYING APPARATUS UTILIZING A LASER BEAM**4,202,110 5/1980 Kooi ..... D10/66 X
4,752,126 6/1988 Fujii ..... 356/140[75] Inventors: **Takumi Hirakawa, Isehara; Hiroyuki Tsuchikane, Zama; Yuichi Ohashi, Hadano; Hidekazu Yamamuro; Shigeyuki Sawaguchi, both of Minami-ashigara, all of Japan***Primary Examiner*—Antoine Duval Davis
Attorney, Agent, or Firm—Bacon & Thomas[73] Assignee: **Sokkia Co., Ltd., Tokyo, Japan**[57] **CLAIM**

The ornamental design for a surveying apparatus utilizing a laser beam, as shown.

[**] Term: **14 Years****DESCRIPTION**[21] Appl. No.: **21,902**[22] Filed: **Apr. 25, 1994**[30] **Foreign Application Priority Data**

Jan. 20, 1994 [JP] Japan 6-00688

[52] **U.S. Cl.** ..... **D10/66**[58] **Field of Search** ..... D10/66; 33/291, 33/292, 293, 294, DIG. 8, DIG. 21; 356/4.5, 138-139, 140, 141.1-141.5, 142, 399-401

FIG. 1 is a front top and left side perspective view of a surveying apparatus utilizing a laser beam, showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.
